UNITED STATES PATENT OFFICE.

THOMAS F. HANDLY, OF ALLEGHENY, PENNSYLVANIA.

PENCIL, PENHOLDER, AND LIKE ARTICLE.

No. 828,737.

Specification of Letters Patent.

Patented Aug. 14, 1906.

Application filed April 2, 1906. Serial No. 308,443.

To all whom it may concern:

Be it known that I, THOMAS F. HANDLY, a citizen of the United States of America, residing at Allegheny, in the county of Allegheny and State of Pennsylvania, have invented certain new and useful Improvements in Pencils, Penholders, and Like Articles, of which the following is a specification, reference being had therein to the accompanying drawings.

This invention relates to certain new and useful improvements in pencils, penholders, and such articles as by force of habit are generally placed in the mouth either to be held or moistened.

The primary object of this invention is to prevent persons from contracting the habit of placing pencils and penholders in their mouths, which is very injurious to health owing to the poisonous nature of the lead within the pencils and the paint and coloring-matter used in decorating the same. To this end I use a compound or mixture having qualities fitted to impart to the taste a sensation as if the tongue had been bitten or subjected to the action of something sharp, acrid, or bitter. The compound or mixture is suitably embedded within the ends of a pencil or penholder, or the lead, wood, or material from which the pencil and penholders are constructed may be coated or saturated with the mixture or compound; but I preferably embed the compound in small quantities within the pencil or penholder, whereby it will not affect the hands of a person handling the articles.

With the above and other objects in view the invention finally consists in the novel construction, combination, and arrangement of parts to be hereinafter more fully described, and pointed out in the claims.

In describing the invention in detail reference is had to the accompanying drawings, forming a part of this application, and wherein like numerals of reference indicate like parts throughout the several views, in which—

Figure 1 is a side elevation of a pencil constructed in accordance with my invention. Fig. 2 is a longitudinal sectional view of the same. Fig. 3 is a plan of a portion of one part of a pencil, illustrating a slight modification. Fig. 4 is a cross-sectional view taken on the line xx of Fig. 3. Fig. 5 is a plan of a "paper" pencil constructed in accordance with my invention. Fig. 6 is a side elevation,

partly in section, of a penholder. Fig. 7 is a longitudinal sectional view of the pencil illustrated in Fig. 5. Fig. 8 is a fragmentary sectional view of the end of a penholder. Fig. 9 is a cross-sectional view of the pencil illustrated in Figs. 1 and 2 of the drawings. Fig. 10 is a similar view illustrating a slightly modified form of construction. Fig. 11 is a cross-sectional view of the pencil illustrated in Figs. 5 and 7 of the drawings.

To put my invention into practice, I use a compound or mixture of a harmless nature having a sharp piercing or stinging taste, which will tend to make a tongue or the skin smart when contacting with the same. Numerous chemical mixtures or compounds of a harmless character can be readily used; but I preferably use a compound prepared by infusing bitter herbs in water—such bitter and aromatic herbs as gentian, quassia, wormwood or weed, aloes, cascara, orange-peel, or such compounds having an intensely bitter and pungent taste. The mixture or compound is preferably prepared in the form of a solution or paste, whereby the lead of a pencil can be coated with the same or the mixture or compound embedded within suitable recesses or concavities provided therefor in the body of the pencil or penholder.

In Figs. 1, 2, and 9 of the drawings I have illustrated the pencil made of two pieces of wood inclosing a stick of lead. The stick of lead, slate, graphite, or other material, which I have designated 1, may be coated or dipped to provide the same with an exterior surface 2 of the compounds or mixtures heretofore mentioned. In lieu of coating or dipping the stick of lead, slate, graphite, or other material 1 the grooves 3 and 4, formed in the pieces of wood 5 and 6, may be coated with the compound or mixture.

The pencil illustrated in Figs. 5, 7, and 11 is similarly constructed to the pencil just described.

In Figs. 3 and 4 of the drawings the portion of the pencil illustrated is provided with a plurality of recesses, notches, or concavities 7, containing a small portion of compound or mixture, while the pencil illustrated in Fig. 10 of the drawings has its grooves 8 filled with the compound or mixture, said grooves being preferably diametrically opposed and extending longitudinally of the pencil.

The penholder 9 (illustrated in Fig. 6 of the drawings) has its end provided with a longitudinally-disposed recess 10, which is filled

with a compound or mixture, while the end of the pendolder 11 (illustrated in Fig. 6 of the drawings) is provided with a plurality of recesses or notches 12, which are also filled with the compound or mixture.

From the foregoing description, taken in connection with the drawings, it will be observed that I have devised a plurality of ways in which the compound or mixture may be 10 embedded within a pencil or penholder for the purpose heretofore mentioned. I do not care to confine myself to the article in connection with which the poignant mixture or compound is used, the compound or mixture, 15 which is of a harmless nature, simply being employed to break children and persons of the habit of placing the ends of pencils in their mouths.

In providing graphite pencils or similar articles with a bitter ingredient, such as aloes, 20 I not only break up the habit of moistening the graphite or lead of a pencil when writing, but prevent school-children from placing the rubber or unsharpened ends of the pencils in 25 their mouths. It is a well-known fact that many diseases are transmitted by germs and microbes being carried from one person to another, and as one child may have placed a pencil in his or her mouth and then given it 30 to another child who places the same pencil in his or her mouth a liability of a disease being transmitted from the first holder of the pencil to the second holder of the pencil is incurred, and it is in view of this injurious 35 habit and practice that I have devised a bit-

ter compound or mixture for pencils, penholders, and similar articles.

Such changes as are permissible by the appended claims may be resorted to without departing from the spirit and scope of the invention. 40

What I claim, and desire to secure by Letters Patent, is—

1. A pencil or like article having a deterrent substance placed therein. 45
2. A pencil, penholder or like article having a bitter mixture or compound placed therein.
3. A pencil, penholder or like article having a bitter mixture or compound concealed 50 therein.
4. A pencil, penholder or like article having a bitter mixture or compound placed therein and extending longitudinally of the article. 55
5. A pencil, penholder or like article having a bitter mixture or compound placed therein, and extending longitudinally of the article throughout its length.
6. A lead-pencil or like article having a bitter mixture or compound placed therein and extending along the length thereof adjacent to the lead-containing bore of the pencil. 60

In testimony whereof I affix my signature in the presence of two witnesses.

THOMAS F. HANDLY.
